(57) **CLAIM**

The ornamental design for a computer fan, as shown and described.

DESCRIPTION

FIG. 1 is a top perspective view of a computer fan showing my new design;

FIG. 2 is a bottom Perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is an enlarged view of detail "9" identified in FIG. 3; and,

FIG. 10 is an enlarged view of detail "10" identified in FIG. 6.

The broken lines in the drawings illustrate the portions of the computer fan which form no part of the claimed design. The dash dot lines in FIGS. 3, 6, 9 and 10 are for the purpose of illustrating the enlarged view indicators and form no part of the claimed design.

1 Claim, 10 Drawing Sheets(56)
